FOLDING SOCKET-HEAD KEY HOLDER

Benjamin H. Smith, South Gate, Calif.

Application May 13, 1948, Serial No. 146,336

Term of patent 14 years

(Cl. D17—14)

To all whom it may concern:

Be it known that I, Benjamin H. Smith, a citizen of the United States, residing at 8649 Garden View Avenue, South Gate, in the county of Los Angeles and State of California, have invented a new, original, and ornamental Design for a Folding Socket-Head Key Holder, of which the following is a specification, reference being had to the accompanying drawing, forming part thereof.

Figure 1 is a view in perspective as viewed from the front of the folding socket-head key holder embodying my new design;

Figure 2 is a bottom face view of the folding socket-head key holder; and

Figure 3 is an end view of the folding socket-head key holder embodying my new design.

The broken lines in the three figures are for illustrative purposes only.

I claim:

The ornamental design for a folding socket-head key holder, substantially as shown and described.

BENJAMIN H. SMITH.
